UNITED STATES PATENT OFFICE.

ERNEST G. LIEBOLD, OF DETROIT, MICHIGAN.

MEANS FOR CARRYING OUT SYSTEMS FOR SAVINGS-ACCOUNTS.

1,284,913.

Specification of Letters Patent. Patented Nov. 12, 1918.

Application filed April 5, 1915. Serial No. 19,102.

To all whom it may concern:

Be it known that I, ERNEST G. LIEBOLD, a citizen of the United States of America, residing at Detroit, in the county of Wayne 5 and State of Michigan, have invented certain new and useful Improvements in Means for Carrying Out Systems for Savings-Accounts, of which the following is a specification, reference being had therein to the accompanying drawings.

This invention relates to means for carrying out a system for savings account whereby a number of subscribers or contributors to a partial payment savings system may be provided for with no bookkeeping and by means that indicate both to the depositors and the depository the state of each customer's or contributor's account at any time. The invention includes the use 15 of index cards as hereinafter shown, which are of a particular kind for each class of contributors so that the officials of the depository have no difficulty in checking in the amounts. The invention also includes 20 means whereby a complete and accurate check and safe guard are provided against irregularities in the receipts or disbursements.

The invention consists in the matters hereinafter set forth and more particularly 30 pointed out in the appended claim.

In the drawings,

Figure 1 is a facsimile reproduction of a 35 depositor's card of a single series showing the method thereon of registering the deposit, in accordance with the features of the invention;

Fig. 2 is a representation of a portion of a 40 depository or bank card corresponding to the depositor's card shown in Fig. 1;

Figs. 3, 4 and 5 are facsimiles of cards of different series respectively than the A card, and

Fig. 6 is a view of a reverse side of a card 45 with a contract agreement thereon.

In carrying out the system, persons wishing to enjoy the use thereof apply for and become members of what is known as a savings club in accordance with rules and regulations agreed upon whereby they pledge 50 themselves to deposit each week before the Monday of the following week, a fixed sum.

If, for example a subscriber to the club 55 wishes to pay the amount of five cents a week, he signs a card similar to that shown

in Fig. 2 on the back of which is printed an acceptance by him of the rules and regulations governing the club and an agreement to abide thereby. He also receives from the depository, bank or like institution a 60 card the facsimile of which is shown in Fig. 1, on the back of which are printed the rules and regulations which he has agreed to and signed for on the duplicate card shown in Fig. 2, hereinafter described as a bank card. 65 On the faces of the cards shown in Figs. 1 and 2 are spaces printed plainly with vertical columns of months as for example starting at March and ending with February, cross ruled into spaces bearing the 70 Monday dates for the entire month in the column in which they occur, with the amount deposited each week, in this instance five cents, and the total sum deposited on each Monday. For example, in the first 75 column to the left in Fig. 1, which is the March column, there are five Mondays dated respectively the 1st, 8th, 15th, 22nd and the 29th and at the 29th space there is inserted the terms "Total, Paid 25c". The card 80 stamped herein as Series A No. — or has a distinctive color or both series indicia and color. The amount and date of deposit of each payment is stamped out or indicated on this card by the space corresponding to 85 the date of the Monday following the day of deposit. For example if the deposit is made on June 21, 1915, it is stamped out at the appropriate square marked 1 in Fig. 1.

At the same time the official depository receiving this sum punches the bank card corresponding in number and series thereto at the same spot. As the rules and regulations require that the bank card is the one that determines the amount deposited at 90 any time, it acts as a check or safe guard against illegal punching of the depositor's card. The cards shown in Figs. 3, 4 and 5 represent series of other denominations, as for example, B series for the ten cent deposit each week, C series for the twenty-five cent deposit and D series for the fifty cent deposit. At the lower right hand corner in the square indicated at 2, Fig. 5 for example, there are shown items or values of the total 95 deposit with accrued interest and a redeposit or savings-account-opening value.

The date of the termination of the series may be at any convenient point and for example in the representation of cards in the 100 105

drawings it is carried past the holidays to the first of March for settlement, as herein shown the depositor is not likely to draw out his account before the holidays as would otherwise happen if the series terminated at that time. As a further incentive to carrying by the normal spending period, as for example the holidays, a penalty is imposed in the rules and regulations which means 10 pecuniary disadvantage to the depositor if this is done.

As a result of this system and the means used in carrying it out, the establishment and maintenance of a savings account is 15 promoted, and a large number of customers can be cared for expeditiously and for very small amounts of deposit which would not warrant the ordinary expensive system of bookkeeping. It enables a small contributor 20 by a weekly payment of an amount that would not be received in an ordinary savings institution, to carry an account to a point where it becomes a sum of sufficient amount to warrant the opening of a regular 25 savings account.

Obviously, changes in the details of construction may be made without departing from the spirit of my invention and I do

not care to limit myself to any particular form or arrangement of parts.

36

What I claim is:—

Means for carrying out a system for savings account comprising series of cards in duplicate, the cards of each series having corresponding series-indicia, each card of a 35 particular series having individual deposit items disposed in monthly vertical columns and weekly cross-horizontal-columns, total deposit items similarly disposed thereon in vertical monthly columns and in weekly 40 horizontal-cross-columns whereby perforation at a stated inter-section of the column denotes the individual deposit and the total deposit at that month and week, one of each pair of duplicate cards having impressed 45 thereon an agreement acceptance blank for the signature of the holder of the card, and each card having a final total item at actual accrued interest and redeposit values.

In testimony whereof I affix my signature 50 in presence of two witnesses.

ERNEST G. LIEBOLD.
